REINFORCED CONCRETE SHIP

Vladimir Yourkevitch, New York, N. Y., assignor,
by mesne assignments, to, Mercantile Metal &
Ore Corp., a corporation of Delaware

Application April 15, 1942; Serial No. 438,983

13. Claims. (Cl. 114—65)

This invention relates to reinforced concrete ships and methods of fabricating the same.

Reinforced concrete ships have usually been built in the same general manner as steel or wooden ships, utilizing the usual ship's form consisting of more or less flat sides, a rounded bottom, and a curved deck. Such ships require the strongest kind of reinforcement of the large flat surfaces which are subjected to high water pressures for, in the case of concrete, it is very dangerous to have it bear bending stresses resulting from pressures exerted against flat surfaces. Consequently this type of ship has so much dead weight that its carrying capacity of useful loads is relatively limited. Furthermore the fabrication of this type of ship required costly and intricate forms. For these and other reasons, concrete ship construction has not been viewed with much favor, notwithstanding economies which should attend the use of reinforced concrete as a construction medium for marine purposes.

Attempts have been made to overcome the disadvantages referred to through the employment of hull shapes wherein flat sides were reduced to a minimum. For example, it has been suggested to cast a ship's hull in the form of a monolith comprising intersecting tubular sections. The use of monolithic intersecting tubular bodies extending uninterruptedly for the full length of the hull minimizes the disadvantage of flat sides and straight side walls, but the intersection of the tubular bodies introduces very considerable dead weight without any particular advantage and with a minimum hull displacement. Furthermore, the intersecting portions of such tubular bodies introduced into the hull tension components and concrete is notoriously weak under stresses of this type, even when reinforced by much steel.

It has also been suggested that concrete hulls be made of truly cylindrical form and monolithic from bow to stern. Such a ship obviously has minimum stability and displacement and consequently relatively low payload carrying power.

With the foregoing considerations and others in mind, it is the object of the present invention to provide a novel method of ship construction whereby the hull may be fabricated from a plurality of individually formed, symmetrical tubular sections, each of which is of substantially circular cross section and of a length equal to a fractional portion of the length of the hull. A plurality of these sections are adapted to be fabricated individually, and a number of them united in end to end relation to produce a substantially

continuous tubular unit extending from the bow to stern sections of the hull and a plurality of these units are adapted to be positioned in substantially tangential relation and permanently anchored to one another to produce, with the bow and stern sections, a complete hull of maximum displacement and payload carrying space and with maximum strength and seaworthiness.

The individual tubular sections may be conveniently formed by centrifugally molding or depositing concrete upon the interior of an exterior form in which is positioned appropriate reinforcing metal bars, so that the employment of interior molds is rendered unnecessary. The individually formed sections may be thereafter united by welding together projecting portions of the reinforcing bars and enclosing the thus welded together portions of the bars in concrete.

Appropriate bulkheads may be formed in or between the respective sections to divide the length of each tubular unit into a plurality of holds provided with hatches and ventilating openings. The tubular units are arranged in parallel, substantially tangential relation and secured to one another in a more or less yielding or elastic manner which will permit some "give" between these units of the hull construction and thus obviate undue bending stresses.

The opposite ends of the tubular units are connected to bow and stern sections, preferably of substantially the same shape and into which the tubular construction may be continued in tapered form in order to provide appropriate reinforcement of these portions of the hull. The ship may have a curved or substantially flat bottom and an appropriately shaped deck, both of which are preferably cast integral for the full length of the hull after the various sections and resulting tubular units have been secured to one another.

The advantage of the present construction is that it will produce an extremely seaworthy ship, well able to withstand the pounding of heavy seas. It will have some give in the connections between the units, and will have a maximum amount of displacement with a minimum amount of construction material. It will provide for convenient disposition and handling of cargos with easy access to holds and quick loading by means of appropriate booms and winches, and piping systems for handling liquid cargos, and it will provide sufficient free board and stability for safe navigation.

Features of the invention, other than those adverted to, will be apparent from the herein-

after detailed description and appended claims, when read in conjunction with the accompanying drawings.

The accompanying drawings illustrate different practical embodiments of the invention, but the constructions therein shown are to be understood as illustrative, only, and not as defining the limits of the invention.

Figure 1 is a side elevation of a ship embodying the present invention.

Figure 2 is a plan view of such ship.

Figure 3 is a section on the line 3—3 of Figure 1.

Figure 4 is a section corresponding to Figure 3, but showing a modified form of the invention.

Figure 5 is a vertical fragmental section on the line 3—3 of Figure 1, showing in enlarged detail method of connecting substantially tangential adjacent tubular units.

Figure 6 is a plan view of the structure shown in Figure 5.

Figure 7 is a fragmental transverse section of the upper portion of one of the concrete sections showing means for anchoring a deck thereto.

Figure 8 is a plan view of the structure shown in Figure 7.

Figure 9 is a view similar to Figure 5, but illustrating a modified form of construction.

Figure 10 is a plan view of the structure shown in Figure 9.

Figure 11 shows consecutive steps in the fabrication of the hull.

Figure 12 shows a completed hull in perspective.

Figure 13 is a longitudinal sectional view of an assembly of consecutive sections of modified form.

Figure 14 is a section on the line 14—14 of Figure 13.

Figure 15 shows a modified form of section.

In order to clearly describe the method of fabricating the hull of the present invention, attention is first directed to Figure 11. The first step of the method is shown at I. Here a suitable exterior form 1 is provided therein with suitably supported metal reinforcing bars 2 extending longitudinally therethrough and projecting beyond the ends of the form 1. The wall of the form is provided with projections 3 forming interiorly thereof mold cavities for lateral anchorages whereby sections to be cast in the form may be subsequently secured to one another in substantially tangential relation. Additional appropriate projections 4 are also provided in the upper and lower portions of the form for casting deck and bottom anchorages and appropriate core elements 5 are also associated with the form for the casting of hatches or ventilating openings. An inner form may also be used if the concrete is to be poured, but, in practice, I preferably eliminate the interior form entirely and use in its stead the revolving head 6 which, rotating at high speed, serves to throw concrete, fed thereto, against the inner face of the form 1 in a manner to deposit it in a substantially uniform layer around the inside of the form and in a manner to enclose the reinforcing bars 2. There may also be formed on the interior of the section annular ribs for reinforcement.

Concrete is used which will properly adhere when thus projected and will provide a substantially waterproof wall of uniform thickness and dimension appropriate to the size of the hull to be formed. The first step of the method thus

consists in its preferred form in centrifugally depositing a tubular section of concrete within the form 1.

After the concrete has set, it is removed from the form and appears as indicated at II in Figure 11. Here the concrete section is shown as comprising a tubular section 7 with lateral anchorages 8, upper and lower anchorages 9, and a hatch opening 10. The reinforcing bars 2 project beyond the ends of the section 7.

The next step of the method consists in bringing two sections 7 into coaxial relation, as indicated at III, with the reinforcing bars 2 of these two sections overlapping. Having brought these sections into this position, the overlapping bars are welded together.

After the bars have been welded together a suitable form is placed about the open welded portion between the two consecutive sections and at the same time the adjacent ends of the two sections may be closed by appropriate flat forms and the open space between the sections thereupon poured to close this space, as indicated at IV, and at the same time to form an integral bulkhead between the sections, so as to divide the unit into adjacent holds, one within each section. These bulkheads may include suitable reinforcing bars and frames if desired and they may also be ribbed for greater strength.

In the manner specified a plurality of successive sections are assembled in coaxial relation to provide one tubular unit. The separate sections may be formed at a distance from one another and brought to a point of assembly and there secured together, or they may be assembled in succession with relation to a pre-formed or a latter formed bow section 12 or stern section 13 which may be cast, pressure-cast, or centrifugally deposited in appropriate forms.

In Figure 11, the aft end of the bow section 12 is shown as butted against one of the tubular units with the interfitting reinforcing bars of both welded together and the space between them cast in to form a bulkhead which at the same time secures the tubular unit to the bow section.

After one of the tubular units has been formed and brought into position with respect to a bow and stern section formed in the manner described, a second and possibly a third or fourth tubular unit is built up in the same way and positioned alongside of and either or both above or below the other units, with the anchorages 8 for securing the several units to one another arranged in interfitting or overlapping relation.

The individual sections may of course be cast in place so that they do not have to be moved, but in any event they finally are in the desired substantially tangential relation shown in Figure 11 and thereupon or in the course of the assembly, they are bolted or otherwise secured together in a manner hereinafter described and the several units are also secured to the bow and stern sections 12 and 13 by casting.

In Figure 11, a hull embodying two units is shown. After these are arranged in the manner stated, a deck 14 and bottom 15 are applied, as indicated at V in Figure 11. These parts are preferably cast in place to extend for the full length of the hull between the bow and stern sections 12 and 13 and they are cast so as to be united to these bow and stern sections and to the intermediate units.

While the deck and bottom may be secured to the tubular units in any desired way, I preferably accomplish this result by building the forms 7 for the deck and bottom, so as to embrace the

anchorage 9 at the top and bottom of the several sections and then make the casts so as to cast about these anchorages and thus assure proper anchoring of the deck 14 and bottom 15 to the assembled units. The section of this hull will be as shown generally in Figure 4.

In Figure 11, the successive sections are shown of substantially uniform thickness throughout their length, but I may, if desired, form these individual sections with flanges 19, so that, in the assembly of these sections, the flanges may be butted together and mechanically secured to one another by bolts or otherwise, either with or without the accompanying welding together of the reinforcing bars of the respective sections. In this construction a bulkhead may be formed at certain assembled flanges, such as shown in section in Figure 13, while other flanges may be left without bulkheads in the assembly. To impart the desired radial stiffness to these sections and to reinforce the same against bending stresses, I may incorporate in the bulkheads suitable reinforcing ribs, as indicated at 18 in Figures 13 and 14 and the use of such reinforcing bracing is not limited to the bulkheads alone as transverse bracing may be incorporated intermediate the ends of the sections without departing from the invention.

I have referred to the use of more than two tubular units and in Figs. 1, 2, 3 and 12, I have shown a hull wherein three such units are employed, the third unit being of smaller diameter and positioned to seat in the reentrant space between the two lower units. This upper unit, indicated at 7a, is made in the same manner as the lower units and is secured to both of them by anchorages corresponding to the anchorages 8. With this arrangement no deck is required, although a flat deck may be cast along the crown of the unit 7a. All of the units of Figures 1-3 are formed and brought together with respect to one another and with respect to the fore and aft sections in the same manner as described with respect to Figures 11 and 12 or 13 and 14.

In the bow section of both forms of the invention described, suitable storage space and crew quarters can be provided while the stern section is adapted to contain crew accommodations, power plant, and other operating adjuncts, etc. Appropriate derricks, booms and other loading and unloading devices, winches, etc., may be mounted on the deck or upon the upper tubular unit 7a, in any suitable manner.

I have referred to the fact that the various units are secured to one another in substantially tangential relation by means of anchorages or couplings indicated generally at 8 in Figure 11. In Figures 5 and 6 I have shown details of these anchorages. Here the various tubular units are provided with overlapping lugs 8 through which are passed pins or bolts 16 of any suitable material. If metal is used in these anchorages they should be fitted through yieldable sleeves, such as rubber sleeves, and washers of rubber or some yieldable or resilient material should be positioned between the several lugs, so as to eliminate the grinding action which would result by interfacial relation between concrete and concrete or concrete and metal. Any suitable cushioning or resilient material may be used in this connection. It is indicated generally in Figure 6 by the reference character 17.

In Figures 5 and 6, the pins 16 are shown as horizontally disposed, whereas in Figures 9 and 10, the lugs 8a which correspond to the lugs 8,

are positioned to overlap in a horizontal direction, and are held together by vertical pins 16a with appropriate cushioning material 17a. These anchorages are placed at intervals throughout the length of the units, so that said units are coupled or tied together at relatively close spacing.

The anchorage of the deck to the tubular units, as described in connection with Figure 11, is shown in Figures 7 and 8. The same construction may be used in securing the ship's bottom 15 to said units.

The invention as thus far described contemplates the casting of individual tubular sections of cylindrical form, the axial assembly of a plurality of these sections to form units, and the subsequent assembly of a plurality of these units in substantially tangential relation and the association therewith of appropriate bow and stern sections. This is the preferred form of the invention. I may, however, as an alternate form, so cast individual sections that each one of them will embody a plurality of tubular members integrally united with one another and preferably with deck and bottom portions after the manner, for example, shown in Fig. 15. Here two tubular shapes 20 and 21 are cast integral with an intermediate rigid and integral joining connection 22 and with an integral bottom 23 and deck 24. Reinforcing bars 25 are shown as projecting from the opposite ends of the section, so that when a plurality of these sections are placed end to end, these projecting portions of the reinforcing bars may be welded together and thereafter encased in cast concrete to join the sections after the same manner as joining the sections 7 in Figure 11. In this way it is possible to assemble integral twin sections in succession to form the hull of a single unit of consecutive, prefabricated sections.

With a ship constructed in the manner described, I obtain maximum buoyancy through maximum displacement with a minimum of material and consequently minimum dead weight and these important factors are gained without sacrifice of stability or maneuverability. If desired, a suitable keel or fins may be cast on the bottom, or on the exterior of the tube assemblies, but I have not shown these as they are not necessary.

I have hereinbefore described the present invention as primarily adapted for employment in the building of reinforced concrete ships. I wish it understood, however, that in the specification of this material I have in mind, if desired, the employment of any suitable natural or synthetic plastic material in lieu of the reinforced concrete described and, consequently, where reinforced concrete is referred to in the claims, it is to be construed as covering such plastic materials as well.

The foregoing description sets forth preferred forms of the present invention, but the invention is to be understood as commensurate with the appended claims.

Having thus fully described the invention what I claim as new and desire to secure by Letters Patent is:

1. The herein described method of constructing concrete ships, which comprises: fabricating a plurality of reinforced concrete tubular sections of hollow cylindrical form, assembling a plurality of these sections in coaxial end to end relation with substantially waterproof joints between them to form a unit, similarly assembling

an additional number of like sections to form a second unit of substantially the same kind, then attaching the two separate units to one another in substantially parallel tangential non-intersecting relation, so that said combined units constitute the main portion of the hull, and uniting the opposite ends of the said connected units to bow and stern hull sections with substantially water-tight joints.

2. The herein described method of constructing concrete ships, which comprises: forming a plurality of units by individually fabricating individual cylindrical tubular sections of reinforced concrete and securing a plurality of them in axial alinement with their contiguous ends secured to one another, arranging the resulting units in substantially tangential non-intersecting relation to one another and securing contiguous units to one another, securing to the forward ends of the thus combined units an appropriate reinforced concrete bow section, and securing to the aft end of the combined units an appropriate reinforced concrete stern section.

3. The herein described method of constructing concrete ships, which comprises: forming a plurality of units by individually fabricating individual cylindrical tubular sections of reinforced concrete and securing a plurality of them in axial alinement with their contiguous ends secured to one another, arranging the resulting units in substantially tangential non-intersecting relation to one another and securing contiguous units to one another, casting a suitable hull bow section and a suitable hull stern section, bringing said bow section and stern section into alinement with the fore and aft ends of said combined units, and uniting the combined units to the bow and stern sections by casting concrete between them.

4. The herein described method of constructing concrete ships, which comprises: successively fabricating a plurality of cylindrical tubular sections of concrete having reinforcing bars therein with the bars projecting beyond the ends of the several sections, bringing said sections into closely spaced axial alinement with the projecting portions of the reinforcing bars of the successive sections substantially contacting with one another, welding the contiguous ends of the bars of the successive sections to one another, then filling in the space between contiguous ends of the successive sections with concrete to form said successive sections into an elongated tubular unit, similarly forming at least one additional unit in like manner, bringing said units into substantially tangential non-intersecting relation and securing them to one another, and attaching to the fore and aft ends of the thus combined units bow and stern sections.

5. The herein described method of constructing concrete ships, which comprises: forming in succession a plurality of reinforced concrete sections of tubular cylindrical form with internal flanges at the opposite ends of each, bringing said sections consecutively into substantially abutting coaxial relation, and securing the flanges of successive sections to one another to form an elongated tubular unit, similarly forming at least one additional unit in the same way, bringing said units into substantially tangential non-intersecting relation and securing them to one another along their lines of substantial tangency, and securing to the opposite ends of the thus combined units appropriate bow and stern sections.

6. The herein described method of constructing concrete ships, which comprises: casting a succession of tubular cylindrical reinforced concrete sections individually, successively arranging said sections in axial alinement, securing the contiguous ends of the successive sections to one another to form an elongated cylindrical unit, similarly preparing at least one additional unit and placing the same along-side of the first, securing the units to one another at adjacent points in their circumferences, casting a reinforced concrete bottom across the space between the lowermost portions of said units and with the bottom secured to both units, and securing appropriate bow and stern sections to said units and bottom.

7. The herein described method of constructing concrete ships, which comprises: casting a succession of tubular cylindrical reinforced concrete sections individually, successively arranging said sections in axial alinement, securing the contiguous ends of the successive sections to one another to form an elongated cylindrical unit, similarly preparing at least one additional unit and placing the same alongside of the first, yieldably coupling the units to one another at adjacent points in their circumferences, casting a reinforced concrete bottom across the space between the lowermost portions of said units and with the bottom secured to both units, and securing appropriate bow and stern sections to said units and bottom.

8. The herein described method of constructing concrete ships, which comprises: casting a succession of tubular cylindrical reinforced concrete sections individually, successively arranging said sections in axial alinement, securing the contiguous ends of the successive sections to one another to form an elongated cylindrical unit, similarly preparing at least one additional unit and placing the same alongside of the first, securing the units to one another at adjacent points in their circumferences, casting a reinforced concrete bottom across the space between the lowermost portions of said units and with the bottom secured to both units, securing appropriate bow and stern sections to said units and bottom, and bridging the uppermost portions of said units between the bow and stern sections with a reinforced concrete deck.

9. The herein described method of constructing concrete ships, which comprises: securing in coaxial end to end relation a plurality of individually fabricated reinforced concrete sections of tubular cylindrical form to produce an elongated tubular unit, forming another unit in the same way, placing said units side by side in laterally spaced apart relation, securing to the fore and aft ends of said units collectively appropriate bow and stern sections, bridging the space between the lowermost portions of said units with a reinforced concrete bottom, and bridging the space across the uppermost portions of said units with a reinforced concrete deck.

10. The herein described method of constructing concrete ships, which comprises: forming a plurality of reinforced concrete, substantially cylindrical tubular units of substantially the same overall length, placing these units side by side in parallel spaced apart relation, yieldably coupling them together, bridging the lowermost portion of said units with a hull bottom, and securing bow and stern sections to the fore and aft ends of the resulting structure.

11. The herein described method of construct-

ing concrete ships, which comprises: forming a plurality of reinforced concrete, substantially cylindrical tubular units of substantially the same overall length and provided at spaced apart distances in the length of each with cross axial bulkheads, placing these units side by side in parallel spaced apart relation, yieldably coupling them together, bridging the lowermost portion of said units with a hull bottom, and securing bow and stern sections to the fore and aft ends of the resulting structure.

12. The herein described method of constructing concrete ships, which comprises: forming reinforced concrete bow and stern sections with a bulkhead at the aft end of the bow section, and a bulkhead at the forward end of the stern section, interposing between the bulkheads of the bow and stern sections a plurality of elongated substantially cylindrical tubular units ar-

ranged in parallel spaced apart relation, radially securing said tubular units to one another, and securing the opposite ends of the tubular units to the bow and stern sections.

- 5 13. A reinforced concrete ship hull comprising reinforced concrete bow and stern sections, a plurality of substantially cylindrical reinforced concrete tubular units interposed between and secured to the bow and stern sections in parallel relation to one another and cross axially spaced apart, anchorages projecting radially outward from each of said units to overlap similar anchorages on the other units, locking members extending through the overlapping anchorages of adjacent units, and cushioning material between the overlapping portions of said anchorages and about the locking members to provide some flexibility in the anchorages thus formed.
